UNITED STATES PATENT OFFICE.

JOHN NUTRY, OF RIDGEWOOD, NEW JERSEY.

DESIGN FOR A BANK.

54,763.

Specification for Design. Patented Mar. 23, 1920.

Application filed April 5, 1919. Serial No. 287,847. Term of patent 14 years.

To all whom it may concern:

Be it known that I, JOHN NUTRY, residing at Ridgewood, county of Bergen, and State of New Jersey, have invented certain new, original, and ornamental Design for a Bank, of which the following is a specification, reference being had to the accompanying drawing, forming part thereof.

In the drawing;

Figure 1 is a perspective view illustrating the design for the bank as seen from one side of the bank, and

Fig. 2 is a similar view as seen from the reverse side of the bank.

The new design comprises essentially a hollow casing of general rectangular form, having a handle at its upper side and the casing and handle bearing the ornamental

contour and configurations substantially as illustrated, the configurations appearing upon the front surface of the bank, as seen in Fig. 1, consisting of relatively raised rectangular, circular and diamond shaped portions in the relative positions as indicated, and surrounded by a relatively raised marginal portion, and the configuration appearing upon the reverse surface of the bank, as seen in Fig. 2, consisting of a relatively raised diamond shaped portion.

I claim:

The ornamental design for a bank as shown and described.

JOHN NUTRY.

Witnesses:

L. GESSFORD HANDY,
MAY SCHULZ.
